UNITED STATES PATENT OFFICE.

BONIFACE A. GRASBERGER, OF RICHMOND, VIRGINIA.

DESIGN FOR A DISH.

Application filed July 16, 1923. Serial No. 6,785. Term of patent 14 years.

To all whom it may concern:

Be it known that I, BONIFACE A. GRASBERGER, a citizen of the United States, residing at the city of Richmond, in the State of Virginia, have invented a new, original, and ornamental Design for a Dish, of which the following is a specification, reference being had to the accompanying drawing, forming part thereof.

This design relates to pressed paper dishes for holding ice cream and other similar things.

In the drawing, Figure 1 is a plan view of the dish, from above, showing my design. Fig. 2 is a side view of the dish.

I claim:

The ornamental design for a dish as shown.

In testimony whereof I have affixed my signature.

BONIFACE A. GRASBERGER.
